UNITED STATES PATENT OFFICE

2,485,845

COTTON-PICKER-SPINDLE ROUGHENING
MEANS

John D. Rust, Memphis, Tenn.

Application September 24, 1945, Serial No. 618,105

7 Claims. (Cl. 56—42)

1

My invention relates to cotton picking machines of the kind disclosed in United States Patents No. Re. 19,411 issued January 1, 1935, No. 1,894,198 issued January 10, 1933, No. 2,058,513 issued October 27, 1936, No. 2,023,491 issued December 10, 1935, No. 2,058,514 issued October 27, 1936, No. 2,085,046 issued June 29, 1937, and No. 2,162,750 issued June 20, 1939.

My present invention seeks to provide an improved means for roughening the steel wire spindles of the cotton picking machine.

Other objects will in part be obvious and in part be pointed out hereinafter.

To the attainment of the aforesaid objects and ends, the invention also resides in the novel details of construction, combination and arrangement of parts, all of which will be first fully described in the following detailed description, and then be particularly pointed out in the appended claims, reference being had to the accompanying drawings, in which:

Fig. 1 is a top plan view of a portion of a cotton picking machine embodying my invention, parts being broken away and parts being shown in section.

Fig. 2 is an enlarged detail section on the line 2—2 of Fig. 1.

Fig. 3 is an enlarged detail horizontal section on the line 3—3 of the tubular post in Fig. 2 and a pair of springy rods carried thereby.

Fig. 4 is a detail perspective on an enlarged scale view of one of the shoes.

Referring now to the accompanying drawings, in which like numerals and letters of reference indicate like parts in all the figures, the main frame of the machine includes angle irons 1, 1^a, 1^b, cross bars 1^c, 1^d and longitudinal bar 1^e, 2 the drive shaft, 3 the driven shaft, 4 the conveyor chains, 5 the spindle carrying slats and 5^a the brackets which connect the slats to the chains. The main frame is of known construction and per se is not a part of my present invention.

The spindle roughener is best illustrated in Figs. 2, 3 and 4. A shaft 6 carries a set of spaced rigid discs 7 to the under faces of which are secured abrasive rings 8. The discs 7 are spaced apart by suitable spacers 9 and secured by a nut 10 threaded on the shaft 6 so that the shaft and the discs with their abrasive rings comprise a unitary structure. The shaft 6 is bored at its lower end to set on a pin 11 carried by a bracket 12. The upper end of the shaft carries a swivel head 13 having trunnions 14 to rest in the bifurcated end of an arm 15 pivotally mounted at 16. An adjustable stop 17 limits the distance the

2

arm may rise, and hence limits the lift of the stack of abrasive unit. This unit is resiliently suspended by means of a lever 18 fulcrumed at 19 and held by a spring pressed bolt 20. The lever 18 has its free end inserted in an eye or loop 21 on the arm 15.

22 is a pipe, carried by the frame of the machine. On the pipe 22 is pivoted a rocker 23 one end of which presses on the swivel head 13 while the other end is pivoted to an eye bolt 24 threaded into the upper end of a tubular post 25 on the lower end of which post is a foot 27 which may ride up and down in a fixed guide 26. The post 25 carries suitably spaced pairs of rods 28 having ends 29 on which are carried shoes 30 that project between the adjacent abrasive disc units. When in non-operating position the shoes rest on top of the metal disc elements 7 leaving both the shoes 30 and the abrasive element 8 out of contact with the spindles 32. The shoes 30 have tapered front ends 31 to cause the spindles to ride up over the arms 30 at all times. At the ends adjacent the post 25 guards 33 are secured on the shoes 30 to prevent cotton from being thrown over those ends and accumulating on the arms 28.

An operating arm 34 is secured to the pipe 22, to which the rocker 23 is also secured for the purpose of rocking the rocker 23 and thereby 30 lowering the abrasive unit's shaft 6 and raising the post 25, in consequence of which the spindles 32 will be held in contact with the abrasive. The arm 34 is operated by a piston 35 in a cylinder 36, the piston rod 37 being pivoted to the 35 arm 34. Suitable operating fluid is admitted into the cylinder 36 from a suitable operator-controlled source (not shown, but well known) via a pipe 38.

The shaft 6 is rotated step-by-step at suitable 40 intervals by means of a pawl-carrying-lever 39 pivoted on shaft 6 and having a pawl 40 to engage a ratchet 41 on the upper face of the top disc 7. The lever 39 has a pin 42 which lies in an elongated slot 43^a in a connecting rod 43 that is 45 pivoted to the operating lever 44 (see Fig. 1). The lever 44 is supported in any suitable well known way, on a pivot 44^a.

A rock shaft 45, mounted on the frame of the machine in any suitable known manner, carries 50 fingers 46 that project between the elements of the abrading unit to throw out any cotton that may accumulate there. The shaft 45 is rocked for the purpose by means of a lever 47 connected to the lever 39 by a connecting rod 48, a spring 55 49 serving to return the fingers 46 and the lever

39 to normal position after the lug 50 (carried by the chain 4) has left the operating lever 44.

This application is a continuation in part of my application filed March 29, 1944, Ser. No. 528,586, patented April 27, 1948, Pat. No. 2,440,450.

From the foregoing description, taken in connection with the accompanying drawings, it is thought the construction, operation and advantages of the invention will be clear to those skilled in the art.

What I claim is:

1. In a cotton picking machine wherein is provided an endless conveyor with cotton picking spindle-carrying slats: the improvement which includes a spindle roughening device between the elements of which the spindles are drawn by the endless conveyor; said device comprising a vertical set of abrasive-carrying discs spaced apart on a shaft, a corresponding set of spindle engaging shoes on a post, the shoes projecting in between pairs of said discs and spaced therefrom, the spindles being carried by the conveyor between the abrasive-carrying discs and the shoes, and means for moving said abrasive-carrying discs and said shoes in opposite directions along the axis of said shaft to bring the abrasive surfaces and said shoes into operative engagement with said spindles, said last named means comprising yieldable means for suspending said abrasive-disc-carrying shaft, means for suspending said shoe-carrying post, a rock shaft with a rocker engaging said abrasive-disc-carrying shaft and connected to said post by virtue of which as said rocker is moved to depress the abrasive-disc-carrying shaft it will simultaneously lift said post for purposes described.

2. A spindle roughening device for roughening cotton picking spindles carried through the device: said device comprising a shaft carrying a plurality of abrasive elements spaced apart on the shaft; means for mounting said shaft for longitudinal movement; a post, shoes carried by said post; means for mounting said post for longitudinal movement parallel to that of said shaft; operator-controlled means operatively connected to said post and shaft for simultaneously moving said post and said shaft in opposite directions to press the spindles between said abrasive elements and said shoes.

3. A spindle roughening device for roughening cotton picking spindles carried through the device: said device comprising a shaft carrying a plurality of abrasive elements spaced apart on the shaft; means for mounting said shaft for longitudinal movement; a post, shoes carried by said post; means for mounting said post for longitudinal movement parallel to that of said shaft; operator-controlled means operatively connected to said post and shaft for simultaneously moving said post and said shaft in opposite directions to press the spindles between said abrasive elements and said shoes; and means to impart intermittent rotation to said shaft.

4. A spindle roughening device for roughening cotton picking spindles carried through the device: said device comprising a shaft carrying a plurality of abrasive elements spaced apart on the shaft; means for mounting said shaft for longitudinal movement; a post, shoes carried by said post; means for mounting said post for longitudinal movement parallel to that of said shaft; op-

erator-controlled means operatively connected to said post and shaft for simultaneously moving said post and said shaft in opposite directions to press the spindles between said abrasive elements and said shoes; and means to impart rotation to said shaft.

5. A spindle roughening device for roughening cotton picking spindles carried through the device: said device comprising a shaft carrying a plurality of abrasive elements spaced apart on the shaft; means for mounting said shaft for longitudinal movement; a post, shoes carried by said post; means for mounting said post for longitudinal movement parallel to that of said shaft; operator-controlled means operatively connected to said post and shaft for simultaneously moving said post and said shaft in opposite directions to press the spindles between said abrasive elements and said shoes, said shaft-mounting means comprising an arm, an anchor for one end of said arm, the other end of the arm being operatively connected to said shaft, and a spring-loaded lever connected to said arm for resiliently holding up said shaft.

25 6. A spindle roughening device for roughening cotton picking spindles carried through the device: said device comprising a shaft carrying a plurality of abrasive elements spaced apart on the shaft; means for mounting said shaft for longitudinal movement; a post, shoes carried by said post; means for mounting said post for longitudinal movement parallel to that of said shaft; operator-controlled means operatively connected to said post and shaft for simultaneously moving said post and said shaft in opposite directions to press the spindles between said abrasive elements and said shoes, said post-mounting means comprising a rocker operatively connected to said post at the top, a foot on the bottom of said post, a guide for said foot and a fluid-operated device operatively connected with said rocker, said rocker also operatively engaging said shaft.

7. A spindle roughening device for roughening cotton picking spindles carried through the device: said device comprising a shaft carrying a plurality of abrasive elements spaced apart on the shaft; means for mounting said shaft for longitudinal movement; a post, shoes carried by said post; means for mounting said post for longitudinal movement parallel to that of said shaft; operator-controlled means operatively connected to said post and shaft for simultaneously moving said post and said shaft in opposite directions to press the spindles between said abrasive elements and said shoes, said shoe-carrying post having pairs of rods with bearing ends, and shoes pivoted to and resting on said pairs of rods.
